United States Patent Office

Des. 192,064
Patented Jan. 9, 1962

192,064

AIRCRAFT

Frank A. Petry, 1615 Armacost Ave., Los Angeles, Calif.

Filed Feb. 29, 1960, Ser. No. 59,553

Term of patent 14 years

(Cl. D71—1)

Fig. 1

Fig. 2

Fig. 3

Fig. 4

FIG. 1 is a perspective view of an aircraft embodying my new design;

FIG. 2 is a top plan view thereof;

FIG. 3 is a side elevation thereof, the opposite side being a mirror image of this disclosed side; and

FIG. 4 is a front elevation of the aircraft, the rear being substantially the same in appearance except for the tail as indicated in FIGS. 1, 2 and 3.

I claim:

The ornamental design for an aircraft, substantially as shown and described.
